(57) **CLAIM**

The ornamental design for a laser gun sight, as shown and described.

DESCRIPTION

FIG. 1 is a perspective view of a laser gun sight according to the present invention.

FIG. 2 is a first side view of the present invention.

FIG. 3 is a second side view of the present invention.

FIG. 4 is a front view of the present invention.

FIG. 5 is a rear view of the present invention.

FIG. 6 is a top plan view of the present invention; and,

FIG. 7 is a bottom plan view of the present invention.

The broken line showing of portions of the laser gun sight is included for the purpose of illustrating environment and forms no part of the claimed design.
